Colburn & Hanson,

Steam Trap.

No 14,906.

Patented May 20, 1856.

UNITED STATES PATENT OFFICE.

RICHD. COLBURN AND L. W. HANSON, OF NORWICH, CONNECTICUT.

ARRANGEMENT OF SUPPLEMENTAL VALVES FOR HIGH-PRESSURE STEAM-ENGINES.

Specification forming part of Letters Patent No. 14,906, dated May 20, 1856; Reissued February 7, 1865, No. 1,862.

To all whom it may concern:

Be it known that we, RICHARD COLBURN and L. W. HANSON, of Norwich, in the county of New London and State of Connecticut, have invented a new and improved self-acting cylinder cock or valve for the purpose of freeing the cylinder at all times of water and back-steam, of which the following is a full, clear, and exact description, reference being had to the annexed drawings, making part of this specification, in which is represented a longitudinal section through the cylinder of a steam-engine with our improvements attached.

15 In high pressure engines worked by slide valves in proportion as the valves are caused to lap for the purpose of working the steam expansively, a back pressure is produced behind the piston by the failure of the exhaust 20 port to remain open to the end of the stroke and this difficulty is increased in locomotives on account of the smallness of the exhaust passage.

Various efforts have been made to remedy 25 the above difficulty and remove the back pressure from the piston. This we accomplish by the use of a peculiar form and arrangement of self acting cylinder cocks or 30 exhaust valve which is auxiliary to the main exhaust and is operated solely by the steam as it is admitted to the cylinder without the intervention or use of any connections whatever with the moving parts of the machinery.

35 To enable others skilled in the art to understand our invention and to put the same in practice, we will proceed to describe the manner in which we have carried it out.

In the accompanying drawings A is the 40 cylinder; B, the piston; C, C', the steam ports.

f and g are openings in the bottom of the cylinder, to which are adapted the valve boxes E, E'. Within these boxes play the 45 valves K, K' which close the openings h, h', when down upon their seats. The valves are raised by the rods m, m', that rest upon the ends of the vibrating lever L. The operation of these valves is as follows: When 50 steam is admitted through the port C the

valve K is instantly closed and K' opened. A way is thus opened through h' for the exhaust steam, which will remain open during the whole length of the stroke, and until the steam is admitted at the opposite port 55 C' when the valve K' is closed and K opened and the steam from the other side of the piston passes off through the opening h. These valves are entirely self operating and require no connections whatever with the 60 moving parts of the engine for their operation. It will also be perceived that any water that may condense within the cylinder will pass off through the openings f and g each time the valves K, K' are opened. 65

The above described arrangement may be applied to any high pressure engine but is particularly applicable to locomotive cylinders where the exhaust steam is employed to urge the fires. It is not intended to dispense with the ordinary exhaust valve, but simply as auxiliary thereto. By its use a much greater lap may be given to the steam valve without producing any compression 70 behind the piston, and thus a great economy 75 of steam and power is effected.

In the accompanying drawings the steam is represented as exhausting through the opening h, h' into the open air. It is evident however that suitable pipes may be adapted 80 to these openings to conduct the steam and water away as required; in which case the rods m, m' will pass through openings made for the purpose in said pipes, and be suitably packed to prevent leakage if necessary. 85

This improvement is more particularly adapted to locomotives using the link motion.

What we claim as our invention and desire to secure by Letters Patent is— 90

The self acting valves K, K', connected together as set forth for the purpose of freeing the cylinder of water and of back steam in the manner substantially as herein described.

RICHARD COLBURN.
L. W. HANSON.
